UNITED STATES PATENT OFFICE.

ARTHUR S. LANICH, OF BARABOO, WISCONSIN.

MOTION-TRANSMITTING MEANS.

1,255,024.

Specification of Letters Patent. Patented Jan. 29, 1918.

Application filed March 29, 1917. Serial No. 153,439.

To all whom it may concern:

Be it known that I, ARTHUR S. LANICH, a citizen of the United States, residing at Baraboo, in the county of Sauk and State 5 of Wisconsin, have invented new and useful Improvements in Motion - Transmitting Means, of which the following is a specification.

My present invention pertains to motion- 10 transmitting mechanism; and its object is the provision of peculiar and highly advantageous motion - transmitting means, designed more particularly, though not necessarily, for embodiment in a door opening 15 or controlling apparatus.

Other objects and advantageous features of the invention will be fully understood from the following description and claim when the same are read in connection with 20 the drawing, accompanying and forming part of this specification, in which:

The figure is an enlarged, detail view illustrative of my novel motion-transmitting mechanism.

25 8 is a windlass or drum and suitably supported in position. The said windlass or drum is provided with a beveled disk 12, and is mounted on a spindle 10 carried by a base plate 9. A cable (not shown) is designed to 30 be wound upon and suitably connected to the windlass or drum.

The disk 12 is preferably of metal, and opposed to the beveled portion of the same are reversely arranged pulleys 16 which are 35 preferably of paper or other suitable friction-creating material. Said pulleys 16 are keyed or otherwise fixed to a shaft 5 which is journaled in a sleeve bearing 13, mounted on the spindle 10, and provided with a 40 flanged opening 14. At 17 the shaft 5 is provided with a band pulley for its connection with a motor (not shown).

Loosely mounted and held against end- 45 wise movement on the shaft 5 is a collar 18, and connected to said collar is a reversing or control lever 19 that is fulcrumed at 20.

A rod 21 is connected with the lever 19 so that the latter may be manipulated when desired by a person positioned at a distance from the motion-transmitting mechanism. 50 Through the medium of said rod 21 and lever 19 either of the pulleys 16 may be engaged with the disk 12 of the windlass or drum 8, according to the direction in which it is desired to rotate the latter from the 55 shaft 5 which may be rotated by any suitable means.

When the lever 19 is relieved of push or pull, the pulleys 16 rest in neutral positions and hence there is no tendency to rotate the 60 windlass or drum 8.

Having described my invention, what I claim and desire to secure by Letters-Patent, is:

Motion transmission means comprising a 65 spindle having a base plate, a drum rotatable on the spindle and having a disk beveled at its side remote from the base plate, a sleeve bearing fixedly mounted on the spindle at the opposite side of the drum, with reference 70 to the base plate, and having a flanged opening at an intermediate point of its length, a shaft rotatable and movable endwise in the sleeve bearing, reversely arranged beveled pulleys fixed on said shaft and adapted to 75 be alternately engaged with the disk, a collar disposed in the flanged opening of the tubular bearing and loosely mounted and held against endwise movement on the shaft, and a lever connected with said collar and 80 fulcrumed in the flange of the opening at an intermediate point in the length of the tubular bearing.

In testimony whereof I have hereunto set my hand in presence of two subscribing witnesses. 85

ARTHUR S. LANICH.

Witnesses:

H. GROTOPHORST,
JUNE BURTON.
